UNITED STATES PATENT OFFICE.

WILLIAM H. DE WICK, OF BROOKLYN, NEW YORK

BANJO OR THE LIKE MUSICAL INSTRUMENT.

Original application filed September 19, 1922, Serial No. 589,058. Divided and this application filed March 28, 1925. Serial No. 18,952.

The invention relates to stringed musical instruments in which the strings are stopped by the fingers of one hand and "picked", or caused to vibrate by the other hand of the performer and may be applied to banjos, banjorines and similar instruments.

The objects of the invention are to produce an instrument of the character described in which the head, if of parchment or the like, may be properly stretched, and its effective vibrating surface be capable of adjustment as to area; in which vibrations from the back of the head or deck, as the case may be, will be directed forward without perforating the head or deck; in which there will be no parts except the usual neck projecting radially outside the hoop to catch into or injure the clothing of the performer, and in which the sound produced by the vibratory member of the instrument will be augmented and directed.

These and further objects will more fully appear in the following specification and accompanying drawings considered together or separately.

One embodiment of the invention is illustrated in the accompanying drawings in which like parts in all of the several figures are designated by similar characters of reference, and in which

Fig. 1 is a bottom plan view of a banjo embodying the invention,

Fig. 2 is a section on the line 2—2 of Fig. 1,

Fig. 3 is a sectional view of a modification and

Fig. 4 is a detail section of a further modification.

In the drawings 1 designates the hoop member of a banjo to which is secured a neck 2 having the usual fingerboard 3 which projects over a parchment head 4. The head is stretched over one end of an inner annular wall or support 5 by means of hooks 6 engaging a ring 7. The wall 5 is arranged concentrically within the hoop 1.

The wall or support 5 is preferably constructed of wood, and is carried on a resonator or sounding board 8 which latter is of circular form and secured in position within the hoop and spaced below the plane of the head 4. The sounding board is set inward a considerable distance from the bottom of the hoop whereby the space surrounded by the hoop is divided into two cylindrical com-

partments, with the wall 5 within the larger. The outside diameter of the annular wall 5 is somewhat less than the inside diameter of the hoop whereby an annular space 9 is formed between the hoop and wall.

Carried by the wall 5 in parallel relation to the sounding board is a disc 10 preferably of wood having a circular opening 11 in the center thereof. An annular rim 12 also preferably of wood encircles the opening 10, and the upper edge of the rim is on a plane higher than the plane of the upper edge of the wall 5, as shown in Fig. 2 whereby when the head is stretched over the wall, that portion of the head within the area bounded by the rim 12 will be under the maximum tension, and the bridge 13 preferably rests upon this area.

Strings 14 anchored to the usual tail piece 15 pass across the head 4, positioned therefrom by the bridge 13, along the neck 2 to the usual tuning pegs (not shown).

The shanks of the hooks 6, instead of passing through brackets bolted to the exterior surface of the hoop 1, pass downward through the annular space 9 and through the sounding board 8, and are set up to draw the head down over the edge of the wall 5 by means of nuts 16 or other suitable devices, and said nuts lie entirely within the compartment below the resonator 8 where there will be no danger of their being broken or otherwise injured, and where they will not come in contact with the person, or the clothing of the performer.

In Fig. 3 is illustrated a modification wherein the tail piece 15^a is secured to the inner surface of the hoop 1 whereby the exterior cylindrical surface of the hoop will be free of projecting portions except for the neck.

The sound waves set up at the lower side of the head will be reflected by the resonator 8 through the lateral openings 17 in the wall 5 and thence outward through the annular space 9, and the resonance of the rim 12, and its surrounding diaphragm 10 and resonator 8 will be added to that of the head 14.

The disc 10 may be provided with any number of circular grooves 18 whereby rims 12 of different diameter may be seated, and if desired the rim 12 may be omitted to permit the disc 10 to vibrate freely.

It is to be understood that the plane of 110

the upper edge of the hoop may be placed on any desired plane relatively to the head. The head and hooks may project beyond the edge of the hoop, as shown in Fig. 2; or 5 the head may be in the plane of the end of the hoop, as in Fig. 3.

By omitting the tail piece and neck the instrument may be used as a drum or as a tambourine. In this embodiment of the invention, the sounding board may be used as 10 in Fig. 3, or it may be reduced to a mere ring as shown at 8^a Fig. 4.

The hook portion of the member 6 may be above the edge of the hoop 1, as shown in 15 Fig. 2, on the same level as the end of the hoop as shown in Fig. 3, or below the level of the end of the hoop, as shown in Fig. 4.

This application is a division of my co-pending application filed September 19, 20 1922, Patent No. 1,567,359, issued Dec. 29, 1925.

In accordance with the provisions of the patent statutes the principle of the invention has been described, together with the 25 apparatus which is now considered to represent the best embodiment thereof, but it is desired to have it understood that the apparatus shown is merely illustrative, and that the invention may be carried out in 30 other ways.

The invention having been described, what is claimed as new and desired to be secured by Letters Patent, is as follows:—

1. In a musical instrument the combination 35 with an outer hoop, a sound board extending transversely therein, and a ring resting on one side of said board and spaced from the inner wall of the hoop, of a membrane head extending over said ring, and 40 securing devices for the head lying in the space between the ring and hoop and extending through the sounding board, and means

for adjusting them located at the opposite side of the sounding board.

2. In a musical instrument, the combination 45 with an outer hoop, a partition extending thereacross and inset from one of its edges, and a ring mounted on one of the faces of the partition, of a second partition extending inwardly from the ring having a 50 central opening, another ring surrounding said opening, a membrane head extending over and engaging the edges of each of said rings, securing devices for the head extending between the hoop and the first mentioned 55 ring and passing through the first mentioned partition, and means at the opposite side of the latter for adjusting said securing devices.

3. In a musical instrument, the combination 60 with an outer hoop, a transverse partition intermediate the edges of the hoop forming a main sounding board, a ring supported thereon within the hoop, and a perforated partition within the ring spaced from the first mentioned partition and comprising 65 a supplementary sounding board, of a membrane head, stretched across the ring, and means for securing it.

4. In a musical instrument, the combination 70 with an outer hoop, a transverse partition intermediate the edges of the hoop forming a main sounding board, a ring supported thereon within the hoop, and a perforated partition within the ring spaced from the first mentioned partition and comprising 75 a supplementary sounding board, of a second ring supported on the supplementary sounding board arranged with its outer edge projecting beyond the plane of the first mentioned ring, and a membrane head 80 stretched across the edges of the two rings.

This specification signed and witnessed this 26th day of March, 1925.

WILLIAM H. DE WICK.
